UNITED STATES PATENT OFFICE.

KIUCHI FUKAMI, OF KOJIMACHIKU, TOKYO, JAPAN.

DIAL AND CASE OF CLOCKS.

1,136,520.

Specification of Letters Patent. Patented Apr. 20, 1915.

Application filed August 26, 1913. Serial No. 786,802.

To all whom it may concern:

Be it known that I, KIUCHI FUKAMI, subject of the Emperor of Japan, residing at No. 3 Kioicho, Kojimachiku, Tokyo, Japan, have invented certain new and useful Improvements in the Dials and Cases of Clocks, of which the following is a specification.

This invention relates to improvement of the dial and the case of the mantel clock or the wall clock and is designed to provide the dial in the inner concave surface of a "sakazuki" shaped plate (sakazuki is the Japanese winecup which is generally used in congratulation or celebration) made of porcelain, china or wood and the clock work being cased in "itozoko," which is a recess on the back of sakazuki.

The object of this invention is to obtain a very simple but a very handsome dial and case of clock, which can serve as an ornament for the room.

The accompanying drawings illustrate a device of this invention, in which—

Figure 1 is a front view of this device. Fig. 2 is a sectional view thereof. Fig. 3 is a side view. Fig. 4 is a view of the device hung on a wall. Fig. 5 is a perspective view of the supporting frame for the device as it is laid down.

This article is made of a piece of lathed wood, of porcelain or of china in a "sakazuki shape" of proper size and the dial consists of a round plate 1 with a concave surface and the clock work is cased in the "itozoko" 2, the recess on the back and the clock work is fixed therein by means of screws or other suitable means. The plate 1 has a flat central portion with a relatively small central perforation for the passage of the central shaft of the clock works, and the recess for the reception of the clock works is formed by an annular flange projecting rearwardly from the flat central portion of the plate and arranged concentric with and spaced from the central perforation. At the part A a metal support enables the plate to be tilted up and down at will. The supporting member A, which is approximately U-shaped, is composed of spaced sides and a transverse connecting portion, the terminals of the sides being bent inwardly to form pivots 3, which engage suitable bearing sockets 4 of the rearwardly projecting flange of the plate 1 at opposite sides of the said flange. The trans-

verse connecting portion is provided with a central bend 5, and a bottom support or member B, which is also substantially U-shaped, is provided with terminal eyes 6 arranged on the transverse portion of the support A at opposite sides of the said central bend. The transverse connecting portion 7 of the bottom supporting member is bent upwardly to form a projecting portion to engage with the lower edge of the plate 1, as clearly shown in Fig. 3 of the drawing. The transverse portion of the supporting member A and the eyes 6 of the supporting member B form a hinged connection and enable the two members to be arranged at different angles to each other in the use of the device. The bottom support is adapted to be arranged in a horizontal position, with its projecting portion 7 engaged with the lower edge of the plate 1, as illustrated in Fig. 3 of the drawing, and the supporting member A is then arranged to form a brace to support the said plate 1 at an inclination. The bottom supporting member operates to prevent the plate from rolling laterally and upsetting. The supporting members A and B are also foldable to enable the support A to form a hanger. When it is used as a wall clock, the support A is hung upon the wall and suspends the clock, the support B being hung down freely behind in that case.

Since this article is easily made of lathed wood, or porcelain or china, its price is very moderate. But in case one of a superior quality is required such as made of gold lacquered work or inlaid work or porcelain or china with an appropriate design on it, it will serve as an ornament for the room.

Having thus described my invention, what I claim and desire to secure by Letters Patent is—

1. A dial and case for clocks consisting of a plate having a concave front face and provided with a flat dial receiving central portion having a central perforation for the passage of a shaft, and an integral annular flange projecting from the rear face of the plate concentric with and spaced from the central perforation, said flange and flat central portion forming a rear recess adapted to receive a clock movement.

2. A dial and case for clocks consisting of a plate provided with a rearwardly projecting flange and a supporting device composed of two parts hinged together and adapted to be arranged at different angles to each other,

one of the members being provided with spaced projecting pivots engaging the flange of the plate, and the other member being provided at its free end with a projecting portion adapted to be engaged with the bottom edge of the plate.

3. A dial and case for clocks consisting of a plate provided with a rearwardly projecting flange forming a recess, and a supporting device including an approximately U-shaped supporting member having spaced sides and a transverse connecting portion, the terminals of the sides being provided with projecting pivots engaged with the

flange of the plate and a bottom supporting member composed of spaced sides having eyes receiving said transverse portion and a connecting portion bent upwardly and adapted to be engaged with the lower edge of the plate.

In testimony whereof I have hereunto set my hand in presence of two subscribing witnesses.

KIUHICHI FUKAMI.
